CONTAINER FILLING MACHINE

Joseph Gialanella, Newark, N. J., assignor of one-half to Gennaro De Rogatis, Orange, N. J.

Application February 27, 1952, Serial No. 273,653

15 Claims. (Cl. 226—116)

1

The present invention relates to container filling machines, and, more particularly, to machines for filling containers with liquids, which have a tendency to froth or foam when agitated.

The present invention is primarily concerned with improving machines of the type disclosed in United States Letters Patent No. 2,347,858, dated May 2, 1944, and issued to W. H. Weeden. Such machines generally comprise a liquid supply tank; a horizontal header above the supply tank; a plurality of filling heads having an inlet in communication with the tank, an outlet in communication with the header and nozzle means for communicating with the opening of a container to be filled; a pair of chambers each having its lower end in direct connection with an end of the header and each having an outlet in communication with the tank; and means for alternately vacuumizing the chambers and connecting them to the atmosphere, including a check valve at each end of the header and a control valve.

In the operation of such machines, containers are positioned against the nozzle means and the control valve is positioned to exhaust one of the chambers while connecting the other chamber to the atmosphere, whereby the header and the containers in connection with the filling heads are vacuumized to cause liquid to be sucked into the containers from the tank while the check valve at the end of the header connected with the other chamber prevents communication between that chamber and the header. When the containers have been filled, they are disconnected from the nozzle means, thereby breaking the vacuum and stopping flow of the liquid to the containers and nozzle means. The liquid in the filling heads is then drawn into the header, where it passes through the open check valve, at the end of the header opposite at which the check valve has been closed, and enters the chamber with considerable force and velocity, causing splashing and foaming. Another batch of containers is then positioned against the nozzle means and the filling cycle is repeated, but this time the other chamber is vacuumized while the first vacuumized chamber is connected with the atmosphere to permit foam and froth to settle and to return the same together with liquid to the tank.

While many attempts have been made to reduce foaming, promote settling of the foam and to prevent such foam from getting into the vacuum pump, machines in use at present are still subject to these difficulties and disadvantages. It will be appreciated that foaming in-

2

creases the time of the filling cycle because of the time required for the foam to settle, whereby the machines cannot be operated at a speed approaching their maximum filling capacity unless foaming is practically eliminated. Also, any foam or liquid which gets into the pump, regardless how small the amount for each filling cycle, eventually necessitates frequent shutdowns of the machines to enable cleaning of the pump.

Accordingly, an object of the present invention is to provide machines of the foregoing character wherein foaming is greatly minimized and practically eliminated.

Another object is to provide such machines wherein foam is positively prevented from entering the vacuum pump and frequent shutdowns for cleaning the pump are avoided.

Another object is to provide such machines wherein liquid is practically prevented from entering the chambers while vacuumized and any liquid tending to enter the same is rapidly drained therefrom upon connection of the chambers with the atmosphere.

Another object is to provide such machines wherein special provision is made to prevent foaming in the header.

Another object is to provide such machines wherein the filling capacity is greatly increased by reducing the duration of the filling cycle.

Another object is to provide such machines wherein the capacity thereof may be enlarged by making provision for filling a greater number of containers during each cycle without otherwise altering the machine.

A further object is to provide the foregoing improvements in a manner enabling the same to be incorporated in newly built machines or embodied in existing machines.

A still further object is to accomplish the foregoing in a simple, convenient, practical and economical manner.

Other and further objects will be obvious upon an understanding of the illustrative embodiment about to be described, or will be indicated in the appended claims, and various advantages not referred to herein will occur to one skilled in the art upon employment of the invention in practice.

In accordance with the present invention, the foregoing objects are accomplished by connecting the end of the header to pipe means including a downwardly extending section in communication with the liquid supply tank and connecting the lower end of the vacuum chamber and the pipe means section at a point below the bottom

of the chamber, whereby substantially all of the returned liquid flows downwardly into the supply tank and only an extremely small portion thereof, if any at all, is drawn into the chamber. Preferably, the pipe means includes an elbow connected to the end of the header having a passage of about the same cross-sectional area as that of the header, whereby foaming is minimized. The connection between the pipe means section and the chamber is provided by a pipe having a much smaller bore than the header, whereby the tendency for such large quantities of liquid to return into the chamber is eliminated. Other features of the machine are that a check valve is provided in the liquid return pipe above the liquid level of the tank, and that foaming in the header is minimized by directing the liquid withdrawn from the filling heads along the longitudinal axis of the header in a manner to prevent forceful contact with the walls of the header.

In the drawing:

Fig. 1 is a schematic elevational view, partly in section, illustrating a container filling machine in accordance with the present invention.

Fig. 1a is a fragmentary view similar to Fig. 1 in which the vacuum chamber has been eliminated.

Fig. 2 is a fragmentary view similar to Fig. 1, illustrating a modified machine.

Fig. 3 is an enlarged fragmentary sectional view of the connection between the filling head and the header of the machines shown in Figs. 1 and 2.

Fig. 4 is a schematic view of another modified machine.

Fig. 5 is an enlarged fragmentary sectional view of the connections between the filling heads and the header of the machine shown in Fig. 4.

Fig. 6 is a schematic view of another modified machine.

Fig. 7 is a schematic view of still another modified machine.

Fig. 8 is an enlarged fragmentary sectional view of the connections between the filling heads and the headers of the machine shown in Fig. 7.

Referring to the drawings in detail and, more particularly to Fig. 1 thereof, there is shown a container filling machine of the type previously mentioned herein. Generally described, this machine comprises a liquid supply tank 10, a header 11, filling heads 12 (of which only one is shown), a vacuum chamber 14 adjacent each end of the header, a vacuum pump 15, and connections and valving, the construction and arrangement of which will be made apparent hereinafter.

The tank 10 is of the usual construction having a drain pipe 16 connected thereto in which a normally closed valve 17 is connected.

The header is positioned substantially horizontally and is located above the tank, as is customary.

The filling head 12 is of the conventional design used in connection with machines of the type to which the present invention relates, and hence need not be illustrated or described in detail. The filling head generally comprises nozzle means 18 for communicating with the opening of the container 19 to be filled, vacuum production in the system for establishing flow through the nozzle only when the container is positioned in engagement therewith, an inlet having conduit means 20 connected thereto for supplying liquid from the tank and being provided with a check valve 21 at about the liquid

level of the tank, and an outlet connected to the header 11 by a flexible tube 22.

The vacuum chambers 14 extend upwardly above the header 11 but have their bottoms 5 slightly below the header, and are each provided with an upwardly extending pipe 24 terminating adjacent the upper end of the chambers and formed with an opening surrounded by a shield 25. The pipes 24 extend to a valve 26 connected by a pipe 27 to the vacuum pump and are constructed and arranged for alternately connecting the pipes to the vacuum pump and the atmosphere.

Contrary to the usual custom of directly connecting the ends of the header to the chambers, each end of the header has pipe means connected thereto which include an elbow 30 attached to the end of the header, a section 31 extending downwardly and into the tank 10 having a check valve 32 connected therein above the tank for preventing liquid to be sucked upwardly into the pipe means and a by-pass or drain tube 34 connecting the lower end of the chamber and the section 31 at a point below the bottom of the chamber.

The elbows 30 have a passage of a cross-sectional area slightly greater than that of the header and have a gradually downwardly curved wall facing the ends of the header to direct liquid from the header downwardly into the section 31 with a minimum of agitation. As shown herein, the ends of the header are set in the elbows 30 and have a flap-type check valve 35 operable by changes in pressure, as will be described hereinafter. The section 31 has a smaller bore than the header and is adapted to conduct liquid from the elbow by gravity flow to the tank. The tube 34 has a much smaller bore than the header and a somewhat smaller bore than the section 31, and is so dimensioned as to effectively vacuumize the header and to drain any liquid that may enter chamber 14.

As seen in Fig. 2, the header 11 and elbow 30 may be adjacent and outside of the chamber 14 in order to simplify construction of such a machine; and, of course, in this latter instance the joint therebetween will be vacuum tight.

In operating the machine just described the container 19 is positioned against the nozzle 18 as shown, and the control valve 26 is positioned, 50 also as shown, whereby air will be pumped out of the chamber 14 at the left to produce a vacuum therein. As this chamber is evacuated, air is also pumped out of the header by causing the flap valve 35 at the left to open and the flap valve at the right to close. The pipe section 31 is also evacuated due to closing of the check valve 32. The air is also pumped from the container 19 to produce a vacuum, the path of the air removed from the system being from the container to the filling head 12, to the header 11, to the elbow 30, to the section 31, to the tube 34, to the chamber 14, to the opening of the pipe 24, and to the pump 15, via open valve 26. As the container is vacuumized, the filling head is rendered effective to connect its inlet with the nozzle 18 and liquid is drawn into the container by way of the supply pipe 20.

When the container has been filled, it is removed, thereby breaking the vacuum and causing the ball valve 21 to close. A small amount of liquid in the pipe 20 is returned by gravity flow to the tank 10 and excess liquid trapped in the filling head 12 is drawn into the header 11 and into the elbow 30 at the left.

Practically all of this liquid descends into the pipe section 31 and only a very small portion thereof, if any at all, enters the tube 34 to be drawn into the vacuum chamber 14. The amount of liquid that may actually enter the chamber is so small, that none of the same reaches the opening of the pipe 24 adjacent the shield 25, whereby entrance of such liquid into the vacuum pump 15 is effectively prevented.

Upon rotating the valve 26, the chamber 14 at the right is vacuumized, as described in connection with the chamber at the left, thereby causing the valve 35 at the left to be closed to vacuumize the system including the containers, and the chamber at the left is connected to the atmosphere via opening 26' on valve 26 to allow liquid in this chamber, its by-pass tube 34 and its pipe section 31 to return by gravity past the check valve 32 into the tank 10.

The cycle may thereafter be repeated to alternately vacuumize the chambers and condition them for permitting such froth, if formed, to settle and for liquid to return to the tank.

In Fig. 2, a modified machine is partially illustrated, which machine is essentially the same as the machine shown in Fig. 1, except that the vacuum chambers have a much smaller volume and are comparatively short and that the valves 35 may be eliminated. By reason of the indirect connection between the header and the vacuum chambers, so little liquid or froth enters these chambers that they need not be of great height to prevent rising froth from entering the pipes 24.

In Fig. 2 also, the header 11 may be adjacent to chamber 14 instead of passing through it. (In fact, chamber 14 and pipe 34 may be eliminated by connecting the vacuum via pipe 24 directly to the elbow 30, as seen in Fig. 1a; but the flap valves 35 must be then included in the header 11).

In Fig. 3, a preferred arrangement is illustrated for connecting the conduit 22 to the header 11 wherein a tube 40 extends horizontally into the header and has a section 41 formed with an outlet 42 at the end thereof facing in the direction of the longitudinal axis of the header and disposed therein. It has been found that this arrangement further reduces foaming or frothing because liquid entering the header is not directed perpendicularly against the inner wall thereof in a manner which would cause splashing but is directed lengthwise along the header and has an opportunity to settle as it flows towards the elbows 30 at the ends of the header.

In Fig. 4, a machine in accordance with the invention is illustrated schematically, which is essentially like the machine shown in Fig. 2, but has a plurality of filling heads 12 connected to the header. A preferred manner of connecting the conduits 22 of this machine to the header is shown in Fig. 5, wherein the sections 41 of the tubes 40 at the left and right of the header respectively face left and right to balance the flow of fluid in the header.

Another modification of the present invention is shown schematically in Fig. 6, wherein an auxiliary header or filler tube 50 is connected to the main header 11 by a pair of pipes 51 and to the supply tank 10 by a pipe 52; while filling heads 12 are connected to the tank 10 by pipes 20 and to the header 50 by conduits 22. This arrangement illustrates how the capacity of an existing machine may be enlarged, 75

simply by providing a second header to which an additional bank of filling heads can be connected. This is made possible by the effective and rapid operation of machines embodying the present invention, whereby with a vacuum pump of a given size a greater number of containers can be filled simultaneously.

In Fig. 7, still another modified machine is shown schematically, wherein an anti-foam tube 60 is connected by a pair of pipes 61 to the header 11 and has a pipe 62 leading therefrom to the tank 10. The tube 60 is parallel to and preferably in the same horizontal plane as header 11 and serves to collect a predetermined amount of the total excess liquid and returns the same to the tank without all of the liquid passing through the header ends shown in Fig. 1. This arrangement thereby reduces the amount of liquid or froth which possibly could enter the vacuum chambers and even more reliably assures that no liquid will get into the vacuum pump. The arrangement primarily reduces the velocity of the liquid being returned to the supply tank by distributing the liquid between the header and tube 60. Since foaming is a function of liquid velocity, it is practically eliminated. This arrangement also increases the amount of liquid that can be handled and returned per filling cycle to the supply tank and, therefore, increases the production rate or capacity of the machine proportionally. For example, if the anti-foam tube 60 were made equal in size to header 11 and half of the total number of pipes 22 were connected to 60, the velocity of liquid being returned would be approximately one-fourth of that if all the liquid were returned to the single header, as is the case in existing machines.

If desired, one filling head (or more) may be connected to the header 11 and one filling head (or more) may be connected to the anti-foam tube 60, so that the tube acts as a trap for the header. A preferred arrangement for connecting the conduits 22 with the header 11 and tube 60 is illustrated in Fig. 8, this arrangement being essentially in accordance with that described in connection with Figs. 3 and 5.

From the foregoing description, it will be seen that the present invention provides a simple, practical and economical filling machine which embodies improvements to reduce frothing and foaming and their attendant disadvantages and to increase the capacity of the machine. These improvements can be readily applied to newly constructed or existing machines to attain the benefits of the present invention.

In general this invention reduces foaming by (a) reducing the velocity of the liquid being returned, (b) streamlining the liquid flow by preventing splashing and striking any surface at right angles. This invention increases production by (a) elimination of foam, (b) elimination of shut down due to liquid getting into the vacuum pump, (c) shorter operating cycles, and (d) greater capacity for handling the liquid.

As various arrangements may be made in the form, construction and arrangements of the parts herein, without departing from the spirit and scope of the invention and without sacrificing any of its advantages, it is to be understood that all matters are to be interpreted as illustrative and not in any limiting sense.

What is claimed is:

1. In a container filling machine of the class described, the combination of a liquid supply

tank; a substantially horizontal header above said tank; a filling head having an inlet, an outlet and means for communicating with the opening of a container to be filled; conduit means for supplying liquid from said tank to said inlet; a flow communicating connection between said outlet and said header; pipe means connected to said header including a downwardly extending section in communication with said tank; a chamber above said supply tank having its upper end above said header; vacuum producing means; means for establishing communication between said vacuum producing means and the upper end of said chamber; and a tube connecting the lower end of said chamber and said pipe means section at a point below the bottom of said chamber.

2. A filling machine according to claim 1, wherein said conduit means is provided with a check valve for preventing return of liquid to said supply tank.

3. A filling machine according to claim 1, wherein said pipe means section is provided with a check valve at a point above the liquid level of said supply tank for preventing the flow of liquid from said tank to said tube.

4. A filling machine according to claim 1, wherein a check valve is provided for preventing communication between said header and said tube.

5. A filling machine according to claim 1, wherein said pipe means includes an elbow connecting said header and said downwardly extending section.

6. A filling machine according to claim 5, wherein the end of said elbow connected to said header corresponds in diameter to said header, the end of said elbow connected to said section corresponds in diameter to said section, and said section has a smaller diameter than said header.

7. A filling machine according to claim 6, wherein said tube has a smaller diameter than said section.

8. A filling machine according to claim 1, wherein said flow communicating connection between said filling head outlet and said header includes a tubular section extending horizontally into said header and outlet means for said tubular section facing in the direction of the longitudinal axis of said header.

9. A filling machine according to claim 8, wherein said outlet means includes a tubular section formed with an outlet at the end thereof and disposed in alignment with the longitudinal axis of said header.

10. In a container filling machine of the class described, the combination of a liquid supply tank; a substantially horizontal header above said tank; a filling head having an inlet, an outlet and means for communicating with the opening of a container to be filled; conduit means for

supplying liquid from said supply tank to said inlet; a flow communicating connection between said outlet and said header; pipe means connected to each end of said header including a downwardly extending section in communication with said supply tank; a chamber adjacent each end of said header each positioned above said tank and each having its upper end above said header; vacuum producing means; means for selectively establishing communication between the upper ends of said respective chamber and said vacuum producing means and alternatively connecting said chambers to the atmosphere; and a tube connecting the lower end of each of said chambers and its said pipe means section at a point below the bottom of said chamber.

11. A filling machine according to claim 10, wherein said conduit means is provided with a check valve for preventing return of liquid to said supply tank, each of said pipe means sections is provided with a check valve at a point between the liquid level of said tank and its said tube, and a check valve is provided between each end of said header and the point at which said tube is connected to its pipe means section for preventing communication between one end of said header and said chamber adjacent thereto while said other chamber is in connection with said vacuum producing means.

12. A filling machine according to claim 10, wherein each of said pipe means includes an elbow connecting the respective ends of said header and its downwardly extending section.

13. A filling machine according to claim 10, wherein a plurality of said filling heads are provided and said flow communicating connection between each of said filling head outlets and said header includes a tubular section extending horizontally into said header and outlet means for said tubular section facing in the direction of the longitudinal axis of said head and the end of said head nearest thereto.

14. A filling machine according to claim 10, wherein a pair of said filling heads are provided, an auxiliary substantially horizontally disposed header in flow connection with said first mentioned header is positioned above said supply tank, said outlet of one of said filling heads being in connection with said first mentioned header, and said outlet of said other filling head being in connection with said auxiliary header.

15. A filling machine according to claim 14, wherein said auxiliary header is positioned between said first mentioned header and said supply tank, and a conduit connected to said auxiliary header is in communication with said supply tank.
